UNITED STATES PATENT OFFICE

2,248,979

DISCHARGE LAMP

Ernst Friederich and Martin Reger, Berlin-Charlottenburg, and Georg Gaidies, Berlin-Pankow, Germany, assignors to General Electric Company, a corporation of New York

Application September 23, 1940, Serial No. 358,022
In Germany July 14, 1939

5 Claims. (Cl. 176—124)

The present invention relates to electric discharge lamps of the elongated, positive column, low gas pressure type having thermionic electrodes which are provided with heater elements similar to those disclosed in the United States Reissue Patent No. 19,057, issued January 23, 1934. During the starting period of the lamp, that is, when the electrodes are being heated to an electron emitting, arc discharge supporting temperature and before the positive column discharge has started between the electrodes the electrode heater elements are connected across the terminals of a current source. Generally the electrodes consist of an elongated hollow cylinder of sheet metal, such as nickel, having a coating of material of high electron emissivity on the outer surface thereof and the heater elements are mounted inside the hollow cylinder. Usually the special heater current is interrupted during the operation of the lamp and the heater elements are in series with the discharge to serve as a resistance for limiting the discharge current.

Discharge lamps provided with electrodes of the type described above have a number of advantages. The preheating of the electrodes reduces the ignition potential of the discharge and prolongs the useful life of the electrodes by preventing hot spots thereon caused by ionic bombardment when the discharge first starts. During the operation of the lamp the heater elements of the electrodes are maintained at an elevated temperature by the discharge current which flows therethrough and heat the electron emitting material on the electrode to a temperature such that the voltage drop at the electrode and the reignition voltage of the discharge is reduced to a minimum. Further, the resistance of the heating wires can be made of such magnitude, when desired, that no resistance external to the lamp is required.

A disadvantage of such lamps is the interval between the connecting of the lamp across the terminals of a current source and the emission of light by the lamp. The electrodes have an appreciable thermal capacity and do not attain an arc discharge supporting temperature until 20 or 30 seconds or more have elapsed after the heating current starts to flow through the heater elements. The starting potential cannot be applied across the electrodes before the electrodes have attained a discharge supporting temperature without causing hot spots thereon due to ionic bombardment resulting in a short lived lamp.

The object of the present invention is to pro-

vide a gaseous electric discharge lamp or the above type having a long useful life and which emits light immediately on the application of potential to the lamp and before the heated electrodes have attained a discharge supporting temperature. Another object of the invention is to provide a self-contained lamp of the above type. Still further objects and advantages of the invention will be apparent to those skilled in the art from the following particular description and from the appended claims.

The invention attains its objects by providing auxiliary thermionic electrodes for supporting a luminous discharge in the lamp during the interval between the application of the heater current to the heated electrodes and the attainment by said electrodes of an arc discharge supporting temperature. Preferably the auxiliary electrodes are of the filamentary type capable of attaining a discharge supporting temperature practically instantaneously when the heating current is applied to the main electrodes. The auxiliary electrodes are connected in series with the heating elements of the main electrodes and means is included in the circuit to break the series connection therebetween as soon as said auxiliary electrodes have attained a discharge sustaining temperature. Simultaneously a luminous discharge starts between the auxiliary electrodes and the lamp emits light before the main electrodes have attained their discharge sustaining temperature.

In the drawing accompanying and forming part of this specification several embodiments of the invention are shown in which—

Fig. 1 is a side elevational, partly sectional view of one embodiment of the invention;

Fig. 2 is a similar view of another embodiment of the invention and

Fig. 3 is a similar view of still another embodiment of the invention.

Referring to Fig. 1 of the drawing the gaseous electric discharge lamp comprises a tubular, vitreous envelope 1, such as a glass envelope, about 1 meter in length and about 30 mm. in diameter. Said envelope 1 contains a luminosity producing gaseous filling, such as a fixed gas, or a mixture of gases, a mixture of neon and argon, for example, at a pressure of about 2 to 10 mm. 45 When desired, a vaporizable metal, such as mercury, is present in addition to the gas in the envelope 1 and the vapor thereof is luminosity producing during operation. A pair of cooperating electrodes 2 are sealed into said envelope 1. Each 50 of said electrodes 2 consist of a hollow, sheet

metal cylindrical body about 2 cm. in length and about 1.5 mm. to 2 mm. in diameter having a coating of material of high electron emissivity characteristics, such as barium oxide, on the outer surface thereof. An electric resistance element in the form of a wire 3, such as a tungsten wire, is mounted in each of said electrodes 2. One end of said wire 3 is connected to said shell 2 and the other end thereof is connected to a terminal of an alternating current source. The wire 3 is thus connected in series with the discharge between said electrodes 2 during the operation of the lamp. Preferably the voltage drop across each of the wires 3 is 35 to 45 volts when the current value is 100 milliamperes. The lamp 15 is then capable of operation on 220 volts without external resistance.

An electrical conductor 4 connects said electrodes 2 in series across the terminals of the current source. Part of said conductor 4 is cemented to the outer surface of the envelope 1. A bimetallic switch 5 and an electrical resistance 6 are connected into said conductor 4 and both these elements are preferably mounted outside the envelope 1 in a base attached to the end of the envelope 1. Two auxiliary electrodes 7 and 8 are mounted inside said envelope 1 and are connected in series with the heater wires 3, the electrodes 2, the bimetallic switch 5, the auxiliary resistance 6 and the conductor 4 across the terminals of the alternating current source during the starting of the lamp. The auxiliary electrodes 7 and 8 consist of a filament of high melting point metal, such as tungsten, and a body of high electron emissivity characteristics, such as barium oxide, or thorium, mounted in heat receiving relation thereto. Said electrode 8 is wrapped around sleeve 10 supporting one of the electrodes 2.

When a suitable potential is applied across the terminals of the lamp a heater current flows through the shunt circuit above described. This current is limited by the heater elements 3 and the auxiliary resistance 6 and is sufficient to heat the electrodes 7 and 8 to an electron emitting, discharge supporting temperature almost instantaneously, that is, within a second or less. The bimetallic switch 5, which has a resistance heater therein, opens when the electrodes 7 and 8 have been heated to a discharge supporting temperature. The opening of the switch 5 causes a potential difference between the electrodes 7 and 8 of sufficient magnitude to start an arc discharge therebetween. The lamp thus emits light almost immediately upon being connected into the current supply circuit.

The arc discharge current flows through the heater elements 3 which raise the electrodes 2 to a temperature such that they are capable of supporting the arc discharge without the occurrence of destructive ionic bombardment thereat in about 20 to 30 seconds after the starting of the arc discharge incident at the electrodes 7 and 8. When said electrodes 2 have attained such temperature the arc discharge transfers from the electrodes 7 and 8 to the electrodes 2 because the distance between said electrodes 2 is shorter than that between the electrodes 7 and 8. The same result is attained by using materials of higher electron emissivity for the electrodes 2 than for the electrodes 7 and 8 or by using other known means for making the electrodes 2 more capable of supporting the discharge than the electrodes 7 and 8 after the preliminary heating of the electrodes 2.

The electrodes 7 and 8 support a discharge for a short time only each time the lamp is started. As a result they have a long useful life even when said electrodes have such small thermal capacity that they are heated to a discharge supporting temperature almost immediately by the heating current or when they comprise electron emitting materials which are highly emissive but which would have a short useful life if said electrodes 7 and 8 were used alone in the lamp for supporting the discharge.

The auxiliary resistance 6 is constructed in such manner, when desired, that the electrical resistance thereof increases rapidly with increasing temperature. Preferably the resistance thereof increases 5 to 10 times its original value. The potential difference between the electrodes 7 and 8 is thus rapidly increased to a value such that the discharge starts therebetween and, when desired, the value of the resistance 6 is of such magnitude that the switch 5 is not necessary and is omitted.

Other types of current interruptors are used in place of the switch 5 when desired. For example, 25 a discharge device having a higher discharge maintaining voltage than the voltage available in said shunt circuit during the operation of the starting discharge in the lamp is useful.

The embodiment shown in Fig. 2 of the drawing 30 is similar to that shown in Figure 1 except that in this embodiment the auxiliary electrode 10 is separated such a distance from the lead 11 connected to the conductor 4 that a short electric discharge takes place between these elements before the discharge starts between the electrode 10 and the corresponding electrode at the opposite end of the lamp. The electrode 10 is thus rapidly heated and the starting of the discharge between said electrode 10 and the corresponding electrode at the opposite end of the lamp facilitated. The short electric discharge is extinguished to break the shunt circuit when the discharge starts between the electrode 10 and the corresponding electrode at the opposite end of the lamp.

The embodiment of the invention illustrated in Fig. 3 of the drawing is similar to that shown in Figs. 1 and 2 except that in this embodiment a hydrogen filled iron wire resistor 11 is connected into the current leads of one of the electrodes 2 and a resistance element 9 having a negative thermal resistance characteristic, such as an oxide body, is also connected into one of said leads or into the circuit between the electrode 2 and the electrode 7. The resistance of the element 9 decreases as the temperature thereof increases. The resistor 11 has a regulating range of about 13 to 39 volts at 100 milliamperes.

When the lamp is connected across the terminals of an alternating current source current flows through the shunt circuit including the conductor 4 and the lamp starts into operation in the same manner as the lamp illustrated in Figs. 1 and 2. In this embodiment, however, during the interval between the starting of the discharge between the electrodes 7 and 8 and that between the electrodes 2 the discharge current is limited by the resistances 3, 9 and 11. While the resistance of the elements 3 increases as the temperature thereof increases the resistance of the element 9 decreases as the temperature thereof increases and at about the same rate so that the discharge current flowing through the circuit during this period is restricted to a range not 70 exceeding the regulating range of the resistor 11.

The stabilizing resistor 11 thus minimizes the influence of line voltage fluctuations on the luminous output of the lamp when the discharge is incident at the auxiliary electrodes 1 and 8 and when said discharge is incident at the electrodes 2. When the lamp has attained operating equilibrium, the voltage drop in the discharge is about 155 volts, that across the resistor 11 is about 25 to 30 volts and that across the two filaments 3 totals about 40 volts. The lamp is thus capable of operating on potentials of 220 volts.

When desired, the envelope 1 of the lamps described above has a coating of luminescent material mounted in light receiving relation to the luminous discharge, such as by being applied to the inner surface of the envelope; or said envelope 1 consists in whole or in part of luminescent glass.

What we claim as new and desire to secure by Letters Patent of the United States is:

1. An electric lamp comprising in combination, a vitreous envelope, a luminosity producing gaseous filling therein, a plurality of thermionic operating electrodes having an appreciable thermal capacity and a plurality of thermionic starting electrodes having a relatively inappreciable thermal capacity sealed into said envelope, the circuit including the discharge path between said operating electrodes having a lower resistance than that including the discharge path between said starting electrodes when all of said electrodes are at a discharge sustaining temperature, heater elements for said operating electrodes, a shunt circuit for connecting said heater elements and said starting electrodes in series for heating said starting electrodes, resistance increasing means connected between said starting electrodes in said shunt circuit to increase the potential difference between said starting electrodes to cause a luminous discharge to start there-between before said operating electrodes have attained their operating temperature, said heater elements being connected in series with the discharge between said starting electrodes and that between said operating electrodes to limit the discharge current and to raise and maintain said operating electrodes at a discharge sustaining temperature.

2. An electric lamp comprising in combination, a vitreous envelope, a luminosity producing gaseous filling therein, a plurality of thermionic operating electrodes having an appreciable thermal capacity and a plurality of thermionic starting electrodes having a relatively inappreciable thermal capacity sealed into said envelope, said starting electrodes being separated a greater distance in said envelope than said operating electrodes, heater elements for said operating electrodes, a shunt circuit for connecting said heater elements and said starting electrodes in series for heating said starting electrodes, resistance increasing means connected between said starting electrodes in said shunt circuit to increase the potential difference between said starting electrodes to cause a luminous discharge to start there-between before said operating electrodes have attained their operating temperature, said heater elements being connected in series with the discharge between said starting electrodes and that between said operating electrodes to limit the discharge current and to raise and maintain said operating electrodes at a discharge sustaining temperature.

3. An electric lamp comprising in combination, a vitreous envelope, a luminosity producing gaseous filling therein, a plurality of thermionic

operating electrodes having an appreciable thermal capacity and a plurality of thermionic starting electrodes having a relatively inappreciable thermal capacity sealed into said envelope, said operating electrodes having a higher electron emission than said starting electrodes during operation of said lamp, heater elements for said operating electrodes, a shunt circuit for connecting said heater elements and said starting electrodes in series for heating said starting electrodes, resistance increasing means connected between said starting electrodes in said shunt circuit to increase the potential difference between said starting electrodes to cause a luminous discharge to start there-between before said operating electrodes have attained their operating temperature, said heater elements being connected in series with the discharge between said starting electrodes and that between said operating electrodes to limit the discharge current and to raise and maintain said operating electrodes at a discharge sustaining temperature.

4. An electric lamp comprising in combination, a vitreous envelope, a luminosity producing gaseous filling therein, a plurality of thermionic operating electrodes having an appreciable thermal capacity and a plurality of thermionic starting electrodes having a relatively inappreciable thermal capacity sealed into said envelope, the circuit including the discharge path between said operating electrodes having a lower resistance than that including the discharge path between said starting electrodes when all of said electrodes are at a discharge sustaining temperature, heater elements for said operating electrodes, a shunt circuit for connecting said heater elements and said starting electrodes in series for heating said starting electrodes, resistance increasing means connected between said starting electrodes in said shunt circuit to increase the potential difference between said starting electrodes to cause a luminous discharge to start there-between before said operating electrodes have attained their operating temperature, said heater elements being connected in series with the discharge between said starting electrodes and that between said operating electrodes to limit the discharge current and to raise and maintain said operating electrodes at a discharge sustaining temperature, and voltage regulating means connected into the current lead to one of said heater elements to minimize the effect of line voltage fluctuations on the luminous output of said lamp.

5. An electric lamp comprising a sealed envelope containing a luminosity producing gaseous filling and a plurality of thermionic electrodes, said electrodes being mounted in spaced pairs, one electrode of each pair having an appreciable thermal capacity and the other electrode a relatively inappreciable thermal capacity, said electrode of higher thermal capacity comprising a heater element connected in series with the discharge path between said pairs of electrodes, means to connect all of said electrodes in shunt to said discharge path, the resistance of said path being higher than the resistance of said shunt circuit before said electrodes of inappreciable thermal capacity have attained a discharge supporting temperature and lower than that of said shunt circuit after said electrodes have attained such temperature.
